UNITED STATES PATENT OFFICE.

OTIS A. MYGATT, OF NEW YORK, N. Y.

DESIGN FOR A REFLECTOR FOR ARTIFICIAL LIGHTS.

SPECIFICATION forming part of Design No. 35,756, dated February 18, 1902.

Application filed June 3, 1901; Serial No. 63,049. Term of patent 7 years.

To all whom it may concern:

Be it known that I, OTIS A. MYGATT, residing at New York, in the county of New York and State of New York, have invented and produced a certain new and useful Design for a Reflector for Artificial Lights, of which the following is a specification, reference being had therein to the accompanying drawing.

The design relates to the form or configuration and surface ornamentation of a reflector for artificial lights.

The drawing shows a side elevation, partly broken away, of a reflector embodying my design.

The form of the body of the reflector is the frustum of a hollow cone A, surmounted by a plain ring B. The outer surface of the body is practically covered by prisms C, arranged spirally. The inner face of the reflector is smooth; but as the reflector is composed of

transparent glass the ornamentation is visible through the glass. The edge of the reflector is scalloped and beaded, as indicated at D.

What I claim, and desire to secure by Letters Patent, is—

The design for a transparent reflector for artificial lights, having the body in the form of a frustum of a hollow cone covered on its outside by prisms arranged spirally, the inner face being smooth, the edge scalloped and beaded, and the cone surmounted by a plain ring, substantially as shown and described.

In testimony whereof I affix my signature in presence of two witnesses.

OTIS A. MYGATT.
